Primary Examiner — David G Muller*(74) Attorney, Agent, or Firm* — Karish & Bjorgum, PC**CLAIM**

The ornamental design for a rounded eye-drop bottle reservoir, as shown and described.

DESCRIPTION

FIG. 1 is side isometric view of one embodiment of a reservoir of the invention.

FIG. 2 is a side view of the reservoir of FIG. 1.

FIG. 3 is front view of the reservoir of FIG. 1.

FIG. 4 is rear view of the reservoir of FIG. 1.

FIG. 5 is top view of the reservoir FIG. 1.

FIG. 6 is a bottom view of the reservoir of FIG. 1; and, FIG. 7 is cross-section view of the reservoir of FIG. 6.

The broken lines shown represent environmental material related to the claimed design and form no part of the claimed design.
